UNITED STATES PATENT OFFICE

2,464,657

DEVICE FOR STRETCHING, CRIMPING, AND
TWISTING CREPE PAPER

Chester E. Stephenson, Columbus, Ohio

Application October 16, 1947, Serial No. 780,200

3 Claims. (Cl. 41—1)

1

The present invention relates to new and useful improvements in crepe paper stretching, crimping and twisting devices for use by show window trimmers or decorators, or for shaping the paper to provide a decorative design or display for other purposes.

More specifically the invention embodies the provision of a U-shaped rod or shaft on which one end of the crepe paper is rolled to stretch the paper and by means of which the paper may be twisted to a desired shape or design.

An important object of the present invention is to provide slides on the shaft for compressing the rolled paper thereon to form pleats therein.

Another object of the invention is to provide a device of this character on which one end of the paper may be rolled for holding the paper without danger of tearing or otherwise damaging the same while tacking the rolled end to a store shelf or other structure.

A still further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a front elevational view showing the use thereof as a paper stretcher;

Figure 2 is a similar view showing the slides compressing the rolled end of the paper to form a pleat therein;

Figure 3 is a front elevational view illustrating the use of the device for twisting the paper;

Figure 4 is an enlarged perspective view of the U-shaped shaft, and;

Figure 5 is an enlarged fragmentary sectional view taken on a line 5—5 of Figure 1.

Referring now to the drawing in detail wherein for the purpose of illustration I have disclosed a preferred embodiment of the invention the numeral 5 designates a U-shaped shaft preferably constructed of rigid strap metal, or other suitable material shaped to provide a longitudinal slot 6 which is open at one end of the shaft. A pair of metal loops or slides 7 are slidably mounted on the shaft.

The shaft is used for stretching crepe paper as shown in Figure 1 of the drawing by attaching one end of the paper to a floor by tacks or the like 8 and rolling the other end of the paper on the shaft 5. The slides 7 are placed on the shaft at each edge of the paper to hold the paper thereon while being rolled. The rolled end of the paper is then tacked to a shelf or other structure 10 by tacks 11 driven through the roll and through the slot 6 of the shaft. The slide 7 at

2

the open end of the slot is then removed and the shaft withdrawn from the rolled end of the paper.

The paper may be pleated as shown in Figure 2 of the drawing by tacking one end of the paper to the floor as heretofore described and rolling the other end of the paper on the shaft and then moving the slides 7 inwardly to compress the roll and thus form the pleats as shown at 12. The compressed roll 13 may be secured in its compressed position by one or more tacks 14 driven therethrough and passing through the slot 6 of the shaft.

The device may also be used for twisting the paper at an intermediate portion as shown at 17 to shape the paper into upper and lower triangles 16 and 17, the ends of the paper being secured to hold the paper in its twisted position as heretofore described.

It will be apparent that various other shapes and designs may be made in the paper through the use of the shaft on which one end of the paper is rolled.

In view of the foregoing description taken in conjunction with the accompanying drawing it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A stretching and shaping device for sheet material comprising a pair of parallel bars interconnected at one end on which one end of the material is rolled and a pair of members slidable on said bars adapted to compress the rolled material.
2. The combination of claim 1 wherein said parallel bars are rigid.
3. The combination of claim 2 wherein said slideable members are sleeves engaging both of said bars.

CHESTER E. STEPHENSON.
